Primary Examiner — Marie D. Fast Horse(74) *Attorney, Agent, or Firm* — Revolution IP, PLLC(57) **CLAIM**

The ornamental design for a wall-mounted POS device, as shown and described.

DESCRIPTION

FIG. 1 is a perspective view of a wall-mounted POS (point of sale) device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
